NORMAN D. FULTON, OF WILMINGTON, DELAWARE, ASSIGNOR TO HERCULES POWDER COMPANY, OF WILMINGTON, DELAWARE, A CORPORATION OF DELAWARE.

METHOD AND APPARATUS FOR PACKING CARTRIDGES.

Application filed September 21, 1927. Serial No. 220,909.

This invention relates to a machine for packing gelatin dynamite into shells and closing the shells to form cartridges. More particularly it relates to a machine in which the feeding of the dynamite is automatically discontinued when the desired charge has been fed into the shell, and in which the dynamite is cut off adjacent the top of the shell, tamped into the shell, and the shell subsequently closed by crimping the open end.

An object of this invention is the provision of a machine for filling shells with gelatin dynamite which is provided with a knife for severing the dynamite adjacent the top of the shell thus insuring that an accurately measured charge is introduced into the shell. A further object is the provision of an improved method for filling dynamite cartridges which method is advantageously carried out by the machine.

In the drawings:

Fig. 1 is an elevation of the front of the machine;

Fig. 2 is a vertical section on line 2—2—2 of Fig. 1;

Fig. 3 is a plan view of the dynamite cutting knife;

Fig. 4 is a sectional view showing the operating devices for the knife and its relation to the dynamite feeding mechanism;

Fig. 5 is a plan view of the tamping rod carrying plate;

Fig. 6 is a plan view, partly in section, showing the mounting of the tamping rods and their relationships to a shuttle filled with shells prior to the tamping operation;

Fig. 7 is a view similar to Fig. 6 showing the tamping operation; and

Fig. 8 is a sectional view of the valve which controls the feeding of the dynamite.

The machine comprises a suitable frame 2 on which are mounted the various operating parts of the machine. A hopper 4 is provided with a feed screw 6 mounted on a shaft 8 which is supported by a piston in cylinder 10 in the usual manner. A power driven shaft 12 is coupled by means of a clutch 14 to a shaft 16 carrying gear 18 which meshes with a gear 20 splined to shaft 8 to drive the feed screw without, however, preventing vertical movement of shaft 8 with the piston. The clutch is controlled by a lever 22 operated by a piston in cylinder

24 in a manner hereinafter described. The bottom of the hopper is provided with nipples 26 through which the dynamite is fed into the shells.

A spider 28 carries tables 30 provided with carrying rods 32 mounted for vertical movement in the spider. Vertical movements are imparted to the rods 32 by means of plungers 34, 38 and 42 carried, respectively, by cylinders 36, 40 and 44.

Each of rods 32 carries a projection 46 arranged to engage a lever 48 the lower end of which is arranged to engage a stem 50 of a valve 52 of suitable type. Valve 52, upon actuation of stem 50 simultaneously connects cylinders 36, 40, and 44 to a supply of compressed air whereby plungers 34, 38 and 42 are actuated to raise tables 30. Spider 28 is moved step by step manually by the operator. As shown, spider 28 carries four tables 30. When one is aligned with plunger 34, two others are aligned with plungers 38 and 42. Lever 48 is engaged by a projection 46 when the corresponding rod 32 moves over plunger 34. It will be understood, therefore, that as soon as a rod 32 reaches this position, it will be raised by plunger 34.

Reference to Fig. 2 will show that, when a rod 32 is raised, projection 46 will clear the end of lever 48, allowing it to swing out from stem 50, and therefore the supply of air will be cut off. The compressed air in the cylinders will, however, maintain the plungers in raised position. When projection 46 is again lowered, it will pass beyond lever 48, which is eccentrically mounted. Accordingly, valve 52 is actuated only once by each table as it moves to filling position.

Each of cylinders 36, 40 and 44 is connected to exhaust through a valve 54 and pipe 56, which is connected to a pipe 58 leading into a bore in a valve 60 in which slides a piston 62 having a projection extending downwardly through the bottom of the valve and having a small hole 64 therethrough arranged for alignment with pipe 58 and a pipe 66 communicating with the atmosphere when the piston is in an intermediate position in its stroke. The piston is normally held downwardly by a spring 68 in a position in which the piston closes the entrance 58.

Plunger 34 is provided with an adjustable

projection 70 arranged to engage the protruding end of piston 62. The rise of plunger 34 is very rapid, so that hole 64 is carried upwardly past 58 and 66 without any appreciable loss of air from the cylinders. During the period in which plunger 34 is in raised position, entrance 58 is closed by that portion of piston 62 below hole 64.

Communicating with pipe 58 is another 10 pipe 72 to which is connected pipe 74 communicating with the upper end of cylinder 10. Pipe 74 is also connected with valve 52. A pipe 76 at the bottom of cylinder 10 communicates constantly with a supply of compressed air. When the upper end of cylinder 10 is exhausted, the pressure at the bottom thereof acts below the piston and maintains feed screw 6 in raised position. Actuation of valve 52 admits air through pipe 74 20 above the piston which then drops due to its own weight and that of parts which it carries, since the pressures above and below balance each other. When exhaustion takes place through valve 60, the pressure above 25 the piston is removed and the feed screw will rise.

Cylinder 24 is similarly provided with pipes 78 and 80, 78 communicating with pipe 72 and valve 52, while pipe 80 communicates constantly with a supply of compressed air. The piston is normally held to the right end of the cylinder 24, (as viewed in Fig. 1), against the pressure of a spring by the pressure on its left side, but, upon 30 actuation of valve 52, it is forced to the left by the spring since the air pressures on both sides of the piston become equal. When the piston moves to the left the clutch is engaged and the feed screw driven. 35 A knife 82, carried by rods 84, fitted with pistons 86 which operate in cylinders 88, reciprocates directly under the feeding nipples 26. By actuation of a suitable valve, the operator may at will admit air to either 40 end of the cylinders to actuate the knife when desired.

Positioned above plunger 38 are tamping rods 90, suitably aligned to cooperate with the shells and carried by a plate 92 in any 45 suitable manner. Similarly positioned above plunger 42 is a crimping mechanism 94 of the common type.

Shells A are placed in a shuttle B which is positioned by an operator on a table 30 50 located in the position of the one shown at the extreme left by Fig. 2. The table is then moved to a position over plunger 34. As it approaches this position, valve 52 is actuated producing an upward movement of 55 plungers 34, 38 and 42 and also allowing clutch 14 to be engaged and feed screw 6 to drop, thus starting the feeding of the dynamite C in the hopper. As plunger 34 rises, it raises table 30, moving the ends of the 60 shells over nipples 26. At the same time, it

will be noted, piston 62 is moved to its extreme upper position.

The dynamite now feeds slowly into the shells until they are full substantially up to the mouths of the nipples. Continued feeding compresses the dynamite and forces the shells and table 30 slowly downwardly against the pressure of the air in cylinder 36. As plunger 34 moves downwardly piston 62 is also forced downwardly until hole 64 is aligned with openings 58 and 66. Since the movement of 62 is slow, exhaustion takes place from pipe 58, allowing plungers 34, 38 and 42 to drop, disengaging clutch 14 and lifting feed screw 6. Because of the rapid drop of shells A, the viscous dynamite is pulled out into contracted rods as shown at D in Fig. 3.

Knife 82 is then actuated by the operator to cut the rods of dynamite between the shells and the nipples immediately above the shells and as close as possible thereto, leaving the dynamite in the upper ends of the shells in the form of truncated cones such as shown at E in Fig. 6.

Spider 28 is then rotated another quarter turn when unfilled shells are brought under the hopper and the filled shells are brought under tamping rods 90. Rise of plunger 38 moves the open ends of the shells over rods 90 and the cones E of dynamite are compressed into the shells as shown in Fig. 7, a yielding pressure being obtained since plunger 38 is moved by compressed air. When exhaustion takes place through valve 60, plunger 38 drops carrying the shells downwardly off rods 90.

A subsequent quarter turn of spider 28 moves the tamped shells under crimping mechanism 94 where the shells are crimped in the usual manner upon the raising and lowering of plunger 42.

It will be noted that this machine is designed to carry out a very simple and efficient method of filling a shell with a desired charge of viscous material such as gelatin dynamite while leaving the upper end of the shell empty so that the walls may be crimped or folded inwardly to close the cartridge. This method consists of partially filling the shell from a supply and then pulling the shell to a distance from the supply so that the viscous charge is drawn into a contracted rod which is cut adjacent the open end of the shell leaving a truncated cone of material which is readily tamped down below the open end of the shell.

What I claim as my invention and desire to protect by Letters Patent is:

1. In a machine for filling a shell with viscous material, means for feeding a charge of material to a shell when the shell and feeding means are located in filling relationship, and cutting means for severing material extending between the feeding means

and the shell after the feeding means and shell have been relatively moved from filling relationship.

2. In a machine for filling a shell with viscous material, means for feeding a charge of material to the shell when the shell and feeding means are located in filling relationship, means for relatively moving the feeding means and shell from filling relationship to produce a tapering rod of material extending from the material in the shell, and, cutting means for severing the rod of material adjacent the shell.

3. In a machine for filling a shell with viscous material, means for feeding a charge of material to the shell when the shell and feeding means are located in filling relationship, means actuated automatically upon the filling of a predetermined charge into the shell to relatively move the shell and feeding means from filling relationship to such relative positions that a tapering rod of the viscous material will extend from the material in the shell, and, cutting means for severing the rod of material.

4. In a machine for filling a shell with viscous material, means for feeding a charge of material to a shell when the shell and feeding means are located in filling relationship, and, cutting means for severing material extending outwardly from the shell after the feeding means and shell have been relatively moved from filling relationship.

5. In a shell filling machine, means for feeding a charge to a shell when the shell and feeding means are located in filling relationship, means actuated automatically upon the filling of a predetermined charge into the shell to relatively move the shell and feeding means from filling relationship, and to interrupt the feeding, and, cutting means for severing material extending outwardly from the shell after the feeding means and shell have been relatively moved from filling relationship.

6. In a shell filling machine, means for feeding a charge to a shell when the shell and feeding means are located in filling relationship, the shell and feeding means being relatively moved during a portion of the feeding operation, means actuated auto-

matically in the relative movement of the shell and feeding means to relatively move the shell and feeding means from filling relationship, and, cutting means for severing material extending outwardly from the shell after the feeding means and shell have been relatively moved from filling relationship.

7. In a machine for filling a shell with a charge of viscous material, means for feeding a charge of material to a shell when the shell and feeding means are located in filling relationship, cutting means for severing material extending outwardly from the shell after the feeding means and shell have been relatively moved from filling relationship, and means for tamping the charge within the shell.

8. In a machine for filling a shell with a charge of viscous material, means for feeding a charge of material to a shell when the shell and feeding means are located in filling relationship, cutting means for severing material extending outwardly from the shell after the feeding means and shell have been relatively moved from filling relationship, means for tamping the charge within the shell, and means for crimping the mouth of the shell to form a closure therefor.

9. In a machine for filling and closing shells, means for presenting a shell successively to filling, cutting, tamping, and crimping means, and means for simultaneously positioning shells in operative relationships to the filling, cutting, tamping, and crimping means.

10. A method of filling a shell with viscous material, which includes feeding material to the shell from a supply through an open end of the shell, drawing the shell and supply relatively apart to produce a contracted rod extending within the shell, severing the rod adjacent the open end of the shell and tamping the material extending beyond the end of the shell into the unfilled portion of the shell adjacent the open end thereof.

In testimony of which invention, I have hereunto set my hand, at Wilmington, Del., on this 19th day of September, 1927.

NORMAN D. FULTON.
